EXHAUST GAS HEATER

Filed Oct. 27, 1926

Inventor:

James J. Sunday

By *Stuart C. Barnes*
Attorney.

UNITED STATES PATENT OFFICE

JAMES J. SUNDAY, OF DETROIT, MICHIGAN, ASSIGNOR TO STANDARD TUBE & MANUFACTURING COMPANY, OF DETROIT, MICHIGAN, A CORPORATION OF MICHIGAN

EXHAUST-GAS HEATER

Application filed October 27, 1926. Serial No. 144,438.

This invention relates to exhaust gas heaters for automobiles, and it has to do more particularly with a heater of the type in which heat from the exhaust gases is transferred to fresh air, which is supplied in a heated condition to the interior of an automobile.

Heaters of this general type have been proposed heretofore, but these have been objectionable because they do not overcome cer-

tain difficulties which are encountered. One of the things which must be guarded against is the creating of a back pressure upon the engine by causing the exhaust gases to flow through the heater. When this occurs the

engine cannot operate efficiently. The heaters heretofore proposed have been of a comparatively large nature in order that the air be adequately heated. A heater which is unduly large is objectionable because it is dif-

ficult to install, and in some automobile structures, it is impossible to install such a heater because of interference by such things as radius rods, and also because of the size of the muffler. Another objection is that when exhaust gases pass through a heater, the pulsations set up a vibration in the heater, or rather in the walls of the heater, so that the pulsations of the exhaust gases are rendered plainly audible.

This invention aims to provide a heater which affords a large heat exchange surface without the necessity of a heater of unwieldy dimensions. Accordingly the heater is of a flat construction as distinguished from one

which is round in cross section, and this construction is advantageous because the heater can be placed angularly and installed in places where the old type of construction could not be installed without extensive structural changes in the automobile construction. The invention contemplates a heater which is shaped so that the exhaust gases are caused to travel therethrough in such a way that the

transfer of heat is efficiently accomplished, and at the same time, the heater does not increase the back pressure of the exhaust gases on the engine. According to the invention the walls of the heater are supported, or braced, so that the pulsations of the exhaust gases

do not set up a vibration which would result in objectionable noises.

A satisfactory form of the invention is shown in the accompanying drawings wherein:

Fig. 1 is a plan view of the heater with a part of the exterior cut away thus showing a part of the interior. 55

Fig. 2 is a sectional view taken on line 2—2 of Fig. 1 showing the exhaust gas chamber, the fresh air chamber, the manner in which the walls are supported, or braced, and showing the additional heat transferring surface. 60

Fig. 3 is a sectional view taken on line 3—3 of Fig. 1 showing how the outer portion of the heater may be secured around the inner portion. 65

Fig. 4 is an end view showing the two inlets, one being for the exhaust gases and the other being for fresh air. 70

Referring to the drawings, the heater will be seen to consist of an interior member 1 and an exterior member 2. The interior member may be made in any desired manner, but it is preferably in the form of a single casting. 75 The member 1 is shaped to form a relatively broad, flat chamber 6 having walls 3 and 4 which are connected together at their ends, as shown at 5.

At opposite ends, this member is provided with openings 10 and 11, one of which is for the inlet of exhaust gases, and the other for the outlet. These openings are preferably round and are adapted to receive the ends of the exhaust pipes 12. The exhaust gases enter one of the openings, pass through the chamber between the walls 3 and 4, and then pass out of the chamber through the other opening. The walls of the exhaust gas chamber are shaped, as shown at 14, so that there is more 90 or less of the gradual change from the circular cross section of the exhaust pipe to the flat, relatively broad cross section of the chamber in the heating unit.

As shown in Fig. 2, the walls 3 and 4 of the 95 exhaust gas chamber are tied together by posts 15. These posts are cast as an integral part of the interior member 1 and serve to bind the walls together and make them rigid so that the tendency of the pulsations of the 100

exhaust gases to set up a vibration in the walls is overcome. By this arrangement no additional noise results in the use of the heater, for even though the gases are caused to be somewhat flattened out so as to flow through the chamber, there is no vibration in the walls of the chamber.

In order to increase the heat exchanging surface, each wall of the exhaust gas chamber 10 is provided with a multiplicity of projections or teats 17. These are also preferably cast integral with the walls.

The outside covering for this interior exhaust gas receiving member is preferably of 15 relatively thin sheet metal. This exterior member is made up of two sections disposed on opposite sides of member 1, and these sections have their edges secured together as by means of a lock seam 20. While other ways 20 of securing the edges of the two members together may be used, the lock seam is advantageous in that the members can be secured around the casting and their edges locked together by a press operation. Each sheet 25 metal piece is provided at each end with an extension 21 which is arcuate in its final form. These are arranged in opposed positions so as to form at one end an inlet for fresh air, and at the other end an outlet. The meeting 30 edges of the extensions, shown at 22 (Fig. 2) may be somewhat spaced apart, or may be overlapped so that a suitable conduit may be placed thereover with the members under compression. In this manner the air conduit 35 may be held in place. The sheet metal portions of the exterior part 2 are drawn down tightly over the projections 17 so that the air is caused to flow around the projections. By this arrangement the projections perform 40 the additional function of supporting the sheet metal walls, and since the walls are supported against vibration, the outer walls are also given support. This structure affords an air heating chamber 25 which is 45 divided centrally by the exhaust gas chamber and which has an inlet and an outlet disposed at opposite ends and communicating substantially equally with divisions of the air heating chamber.

50 It will be understood that the device is inserted in the exhaust line of the automobile, and the exhaust gases pass through the chamber 6. Fresh air is passed through the chamber 25. The supply of fresh air may be 55 obtained from any desired point, and after it passes through the chamber, is then conducted to the interior of the automobile where a suitable radiator may be used. The movement of the gases passing through is slower 60 than the movement in the exhaust pipe, and yet the proportions of the chamber, as compared to the size of the exhaust gas conduit, are such that there is no increase in the back pressure. This slower movement of the 65 exhaust gases through the chamber causes the

walls thereof, and the teats or projections 17 to be adequately heated. The fresh air passing through the passageway 25 contacts with the walls and the projections which afford additional heat transferring surface. The 70 whole structure forms a compact flat unit which can readily be installed, especially since the thickness of the unit is not substantially greater than the diameter of the exhaust line, and which is so constructed that the walls of the exhaust gas chamber are tied together so that they are not subject to vibration, and also the sheet metal walls of the exterior shell are drawn down over the projections so that they too are not readily subject to vibration.

75 While it is advantageous to make the interior member of a casting, the same may be constructed by the use of sheet metal parts, and in this case, the posts may be in the form of bolts or rivets instead of integral parts of the casting. Likewise, the projections which afford the additional heat transferring surface could be in the form of separate pieces 80 affixed to the sheet metal wall, as by means of riveting, welding, or the like; or, the projections may be stamped in the sheet material. The precise number of posts is not material because it would be desirable to have more posts with a larger structure; also, the 85 number of posts used would depend upon the thickness of the walls of the interior unit; thick walls would require a smaller number of posts whereas a thin wall would require a greater number of posts.

90 The exhaust pipe 12 can be connected to the inlets 10 and 11 in any expeditious manner as by the means of a bolt passing through both members. In producing the article, the inlet and outlet may be formed of relatively thick metal, as at 26, and the size may be such as to fit over a small sized exhaust pipe. In case the device is to be installed on a job having a larger exhaust pipe, a larger opening 95 may be obtained by reaming out the openings, the metal being thick enough for the purpose.

100 I claim:

1. An exhaust gas heater comprising a relatively flat member adapted to be inserted in the exhaust line, having a chamber for the passage of exhaust gases therethrough, a multiplicity of projections on opposite sides of this member, and an outside casing over the said member which forms a chamber for the passage of air with the said projections lying within such air chamber to increase the heat transferring surface, said exterior casing lying directly upon said projections whereby the air is caused to flow around the 115 same.

120 2. An exhaust gas heater comprising a member adapted to be inserted in the exhaust line having a chamber for the passage of exhaust gases therethrough, said member being 125

shaped so that a broad, flat chamber is provided, a multiplicity of heat transferring projections on the exterior of said member, and an outside casing over said member which lies directly upon said projections to form a chamber for the passage of air with the projections in such chamber, and posts connecting the walls of the inner member for bracing the walls of this member and the exterior member against vibration.

3. An exhaust gas heater for automotive vehicles which comprises a hollow member adapted to be inserted in an exhaust line, said hollow member being relatively long and relatively flat as compared to the diameter of the exhaust line, and of a width substantially greater than the diameter of the exhaust line, a casing around this member which is shaped similarly to the said member and which is in spaced relation therewith to form an air chamber, the said first mentioned member, together with the casing therearound and spaced therefrom having a combined thickness not substantially greater than the diameter of the exhaust line.

4. An exhaust gas heater for automotive vehicles which comprises a hollow member adapted to be inserted in an exhaust line, and having an opening at each end for the passage of exhaust gases, said hollow member being relatively long and relatively flat as compared to the diameter of the exhaust line, and of a width substantially greater than the diameter of the exhaust line, a casing around this member which is shaped similarly to the said member and which is in spaced relation therewith to form an air chamber, the said first mentioned member, together with the casing therearound and spaced therefrom having a combined thickness not substantially greater than the diameter of the exhaust line, the said casing being shaped to provide an air inlet and an air outlet at opposite ends respectively, and each in close proximity to one of the openings in the first mentioned member and the combined width of the inner member in the casing being not substantially greater than the width necessary to accommodate the two aligned openings at each end.

5. An exhaust gas heater for automotive vehicles which consists of a relatively flat hollow member having openings at opposite ends, said member being adapted to be inserted in the exhaust conduit of an internal combustion engine with the conduit communicating with the openings, and a relatively flat sheet metal member secured around the first mentioned member and in spaced relation therewith to provide an air chamber, said sheet metal member being shaped at its opposite ends to provide an air inlet and an air outlet, said inlet and outlet being disposed at the ends of the heater and each in juxtapo-

sition to and lying in the same plane as one of the openings at the end of the said hollow member.

In testimony whereof I affix my signature
